UNITED STATES PATENT OFFICE

JAMES A. SWEENEY, OF PROVIDENCE, RHODE ISLAND

DESIGN FOR AN OPHTHALMIC MOUNTING

Application filed November 14, 1928. Serial No. 28,869. Term of patent 14 years.

To all whom it may concern:

Be it known that I, JAMES A. SWEENEY, a citizen of the United States, and a resident of Providence, county of Providence, and State of Rhode Island, have invented a new, original, and ornamental Design for Ophthalmic Mountings, of which the following is a specification, reference being had to the accompanying drawing, in which—

Fig. 1 is a front view; Fig. 2 is a plan view; Fig. 3 is a side view of my design; and Fig. 4 is a cross-sectional view, upon an enlarged scale, through one of the rims.

The dominant feature of my design resides in the particular shape as shown in the cross-sectional view with groove inlaid with black or color, the same presenting an ornamental effect for the ophthalmic mounting, rather than a design on the general shape or contour of the ophthalmic mounting.

I claim:

The ornamental design for an ophthalmic mounting substantially as shown and described.

JAMES A. SWEENEY.
